HAIR BRUSH

Murray Schotland, New York, N. Y.

Application July 30, 1956, Serial No. 42,455

Term of patent 14 years

(Cl. D86—10)

Fig. 1 is a top view of a hair brush showing my new design;

Fig. 2 is a side view thereof;

Fig. 3 is a bottom view thereof;

Fig. 4 is a right end view of Fig. 1; and

Fig. 5 is a left end view of Fig. 2.

This application is a continuation-in-part of my application Ser. No. D.41,120 filed April 18, 1956, now abandoned.

I claim:

The ornamental design for a hair brush, substantially as shown.
